PRESSURE SWITCH

Lyle Beeman, Milwaukee, and Edwin W. F. Hanke, Whitefish Bay, Wis., assignors to Allen-Bradley Company, Milwaukee, Wis., a corporation of Wisconsin

Application May 8, 1939, Serial No. 272,388

11 Claims. (Cl. 280—83)

This invention relates to pressure responsive switches and resides in a novel, simplified arrangement of parts in which a principal resilient element opposes the force to be controlled, the same being supplemented by a preloaded resilient member, the supplementing force of which is active through a part only of the travel of the principal resilient member and in which an over center, snap action mechanism is driven by displacement of the principal resilient member in such manner that the forward over center position thereof occurs while the supplemental resilient member is exerting its supplemental action and the return over center position occurs while the principal resilient member is acting without supplement.

One object of this invention is to produce a pressure switch which is compact to a degree greater than can be obtained in the case of pressure switches using the arrangement of parts heretofore employed and in which the principal resilient member resisting the actuating force is preferably in the form of a plate spring.

Another object of this invention is to provide a pressure switch in which a U-shaped frame member may be employed, to the exterior of which a diaphragm and diaphragm chamber may be attached and within which the parts acted upon by the diaphragm may be accommodated and supported.

Another object of this invention is to provide a pressure switch in which the principal resilient member is held in position without complicated supporting means and in a manner permitting movement thereof with a minimum of friction.

Another object of this invention is to provide a pressure switch having an over center snap action on both its forward and return strokes, the response pressures of each of said over center positions being independently adjustable without varying the intensity of the snap action effect.

Heretofore in the art a wide variety of forms of pressure switches have been employed in which the switch members themselves are moved with a snap action and in which the pressures at which the switch functions are subject to regulation. In order to obtain the pressure response desired and the regulation desired these switches have employed a complex arrangement of parts which is difficult and expensive to construct and which is ill adapted to compact formation. Through this invention, however, a switch is provided which is free of the above objections and which is possessed of the novel advantages herein detailed.

This invention is herein disclosed by reference to a specific embodiment thereof described in conjunction with the accompanying drawings which form a part hereof, the same being set forth by way of illustration only and not of limitation.

In the drawings:

Fig. 1 shows a side sectional view of a form of the pressure switch of this invention;

Fig. 2 is a plan view, partly in section and with parts broken away, of the switch shown in Fig. 1;

Fig. 3 is an end elevation, with parts broken away, of the switch shown in Fig. 1;

Fig. 4 is an enlarged detail of some of the movable parts of the switch shown in Fig. 1, showing the relationship of the parts in different positions; and

Fig. 5 is a fragmentary detail showing the method of anchorage of the primary regulating screw.

The switch shown in the drawings derives its structural support from a U-shaped frame member 1, which is shaped to form three sides of a roughly rectangular box. The side corresponding

25 to the bottom of the U is engaged on its exterior face by a diaphragm 2 composed of any suitable flexible material, such as rubberized fabric, the same being securely held in place by screws 3 which pass through a diaphragm chamber 4 into threaded holes provided therefor in the frame 1. Suitable means 5 for connection of the diaphragm chamber 4 with a pressure conduit is securely united with the diaphragm chamber 4, as shown.

30 The face of the frame 1 engaged by the diaphragm 2 is pressed upwardly above the diaphragm and perforated to accommodate a pressure-communicating member composed of a pressure-foot 6 and a thruster 7. The thruster 7 includes two spaced apart, upwardly projecting prongs, as indicated by dotted lines in Fig. 2.

35 Mounted above the thruster 7 is a primary resilient opposing member 8 in the form of a plate spring. The spring 8 includes a raised portion 9, which acts as a thruster seat, which seat is engaged by the prongs of the thruster 7. The resilient portion of plate spring 8 extends to the left of the thruster seat 9, as shown in Figs. 1 and 2, and is held in position to perform its proper function by a pair of ears 10, which extend laterally therefrom at the mid point of its return curve. The ears 10 in turn engage mounting notches 11, formed by pressing inwardly the material of the upstanding portions of frame 1, as shown. The tapered re-entrant portion 12 of the plate spring 8 is notched, as shown at 13,

for engagement with an adjusting nut 14, which is carried upon anchoring bolt 15 and in this manner the resilient opposition to movement of diaphragm 2 is subject to regulation by adjustment of nut 14.

Extending to the right of the thruster seat 9 is an integrally formed portion of the plate spring 8, which, because of pressed-up stiffening ribs 16, acts as a substantially non-resilient lever for the actuation of the switch parts hereinafter to be described. The lever portion of plate spring 8 terminates in a downwardly turned lip 17, which in the standing or "off" position of the switch comes to rest against the frame 1, thus limiting downward movement of the spring 8, preventing undue stressing of the diaphragm 2 while the switch is idle.

The lever portion of plate spring 8 in addition is cut away in its central part to accommodate the elements of a snap-action mechanism of the over center type. This mechanism is pivoted upon a bracket 18 which projects upwardly through the opening in plate spring 8 and which is securely riveted in place upon frame member 1. Bracket 18 bears near its upper end a horizontal groove serving as a seat for a knife edge. Mounted to rock in the groove in bracket 18 is a toggle link 19, which is generally T-shaped in form and which is brought to a sharpened edge at the base of the T for engagement with the bracket 18. A pair of toggle springs 20 join the links 19 with the plate spring 8 under tension to impart to the toggle link 19 over center snap action properties. Springs 20 also serve the function of holding the ears 10 of the plate spring 8 against the notches 11. A raised portion 21 of the frame 1 serves as a lower stop for the toggle link 19, while an actuator bar 22 of a switch 23 serves as an upper stop for the toggle link 19.

For the purpose of furnishing plate spring 8 with a specific amount of resilient reinforcement during a predetermined portion of its stroke, adjustable auxiliary spring 24 is provided. The auxiliary spring 24 is held in place and guided by guide washers 25, which in turn are carried upon threaded post 26. Post 26 is rigidly secured to the bottom of frame member 1, as by a rivet head 27, this rivet serving the dual purpose, if desired, of securing the mounting post 26 in place and holding the bracket 18, as shown. Post 26, further, is provided with an enlarged portion or shoulder 28, against which lower guide washer 25 comes to rest, thus preventing any further downward displacement of the lower end of auxiliary spring 24. The upper guide washer 25 is adjustably held in place by means of the auxiliary adjusting nut 29 provided for that purpose.

The mode of operation of the parts above described is best explained by reference to enlarged detailed view, Fig. 4, wherein the parts are shown by full lines in the standing or "off" position. In this view, for the sake of clarity, toggle springs 20 are omitted and the line of action thereof indicated by dot-and-dash lines. In the standing or "off" position, due to the line of action of toggle springs 20, toggle link 19 is brought to and held by stop 21 in the position of equilibrium shown by the full lines. As the pressure exerted upon thruster 1 increases, plate spring 8 deflects accordingly and as such increase continues the lever end of plate spring 8 comes into engagement with guide-washer 25. Thereafter the thruster 1 acts against the combined resistance of the primary opposition of plate spring 8 and the auxiliary opposition of spring 24. Continued move-

ment thereafter under the influence of the thruster 1 brings the parts to the point where the line of action of toggle springs 20 is coincident with the major axis of the toggle 19. The line indicating this position is designated by the numeral 30. This position is herein referred to for convenience as the "forward over center position," and is the position where, upon continued forward movement, the toggle linkage becomes unstable and passes with a snap action to the position shown by dotted lines. In so doing, the toggle link 19 first gathers momentum and then strikes the switch-actuating bar 22, rapidly forcing the switch 23 to open position. Upon reduction of the effort applied through thruster 1, a return motion of the parts takes place in the following sequence: First, deflection in springs 8 and 24 diminishes to a point where spring 24 comes to rest against shoulder 28 and, thereafter, continued movement of the parts brings them to a return over center position indicated by line 31. It is here noted that during the return passage through the return over center position the thruster 1 is acting against the tension of plate spring 8 only, without the assistance of auxiliary spring 24. Continued motion in a return direction thereafter causes the toggle linkage to snap from the position indicated by dotted lines to the position shown in Fig. 4 by full lines.

By reason of the sequence of movements above described, the pressure switch of this invention may be adjusted with great ease. For example, if the switch is to be employed to regulate a pump supplying fluid to a pressure reservoir and it is desired that the pump go into operation when pressures in the reservoir drop below a designated low-pressure limit, the adjusting nut 14 may be turned until the desired closing characteristics of the switch are obtained. Then, if it is desired that the pump continue in operation until a designated high pressure limit is reached, the adjusting nut 29 is turned until the desired opening characteristics of the switch are obtained. If the adjustments are made in this sequence, the same may be made entirely independently of one another, since the return or closing characteristics of the switch are determined solely by the characteristics of the primary opposing resilient member 8 and the adjustment of nut 14. It is thus apparent that the normal differential between opening and closing pressures, which is due to the characteristics of plate spring 8 and the geometry of the parts, may be augmented to any degree desired by means of the auxiliary spring 24 and as far as this differential is augmented the same is subject to independent adjustment through adjusting nut 29.

While the characteristics of spring 24 are relatively unimportant in obtaining the result above described, we prefer to employ for the purpose, as shown, a pre-stressed resilient member, the resilient reaction of which increases but slightly over the range of displacement employed. With an auxiliary spring having these characteristics, the differential adjustment is easier to secure and maintain.

The circuit-interrupting means 23 may be of any form desired. The form shown in the drawings may be conveniently housed and supported in the frame 1 by providing a switch mounting 32 of insulating material, this being provided on each end with mounting tongues 33, which are received in openings in the vertical standing portions of the frame 1. Assembly is accomplished

by springing the sides of frame 1 while forcing the mounting 32 into position. The switch-actuating bar 22 above referred to is slidingly received and guided in slots formed in the lower side of insulating mounting 32 and carries a pair of loosely held contact bars 34 upon upwardly-projecting lugs 25 provided therefor. To insure proper contact pressure, backing springs 39 are provided. The contact bars 34 are arranged to come into contact with lower contacts carried upon terminal members 36, which are received in lateral recesses in the insulating member 32 and held in place by terminal screws 37.

In order to prevent undue friction in the movement of plate spring 8, adjusting screw 15 is preferably mounted so that it is free to rock and this may be accomplished, as shown in Fig. 5, by receiving the dove-tailed foot 38 of screw 15 in a deeply countersunk aperture in the frame member 1, as shown.

To complete the enclosure of the switch, any suitable cover, not shown, may be provided, such as a strap, or belt, passing around the three open sides of the frame member 1. Suitable conduit-admitting apertures, such as 40, may be provided, and it will be noted that by reason of the substantially parallel disposition of plate spring 8 with respect to diaphragm 2 that ample space for access to the switch 23, for wiring purposes, is easily obtained.

While this invention has been above described by reference to a specific instance of an embodiment thereof, it is intended that the protection of Letters Patent to be granted hereon be not unnecessarily limited thereby, but that such protection extend to the substance of the advance contained in this disclosure and defined in the claims hereto appended.

That which we claim as our invention and wish to secure by Letters Patent is:

1. In a pressure-actuated switch, the combination comprising a U-shaped frame member, a diaphragm and diaphragm chamber secured to the exterior of the bottom of said frame member, a presser-foot engaging said diaphragm provided with a thruster extending into the interior of said frame member, a plate spring having a return bend pivotally carried near said bend upon pivot supports associated with said frame member, said spring being in engagement with said thruster to be deflected thereby, means for adjustably engaging one end of said spring for adjustably tensioning the same, over center snap-action means engaging the opposite end of said spring, and a circuit-interrupting means mounted within said frame member in position to be actuated by said over center snap-action means.

2. In a pressure responsive switch, the combination comprising a mounting frame, a diaphragm and diaphragm chamber secured to one side thereof, a deflectable plate spring mounted on the opposite side thereof and positioned substantially parallel to said diaphragm, a presser-foot engaging said diaphragm and provided with a thruster which extends therefrom through said frame into cooperative engagement with said spring, toggle means including a toggle link and toggle tensioning means associated with said plate spring to be actuated thereby and having a forward and a return over center position, and an auxiliary spring positioned to engage and reinforce said plate spring while passing through said forward over center position only, and circuit-interrupting means actuatable by said toggle means.

3. In a pressure switch of the class described, the combination comprising a U-shaped frame member having a bottom portion and upstanding side portions, apertures in said side portions, circuit-interrupting means between said side portions and secured in place by engagement with said apertures, pressed-in notches oppositely positioned upon the interior of each of said frame side portions, a plate spring having sidewardly projecting ears engaging said notches, means for adjustably locating said plate spring, means for communicating actuating force to said plate spring, and means associated with said plate spring for actuating said circuit-interrupter.
4. In a pressure responsive switch, the combination comprising a plate spring having a bent portion and two ends extending therefrom, means for adjustably locating one end thereof, means for pivotally restraining said spring near the bent portion thereof, means for communicating operating pressures to the opposite end of said spring, a toggle link pivotally carried in position to be actuated by said spring and engaging the same through resilient means tensioned so as to hold the bent portion of said spring in engagement with said pivotally-restraining means, auxiliary adjusting means engaging said spring, and a circuit-interrupter actuatable by said toggle link.
5. In an apparatus differentially responsive to fluctuating actuating force, the combination comprising a primary resilient means, means for communicating fluctuating actuating force to said primary resilient means for deflecting the same from a position of lower stress to a position of higher stress, a toggle member pivoted to turn about a stationary pivot associated with said primary resilient means having a position of equilibrium corresponding to said position of higher stress and a position of equilibrium corresponding to said position of lower stress and having spaced forward and return unstable over center positions corresponding to spaced intermediate positions of said primary resilient means, and auxiliary resilient means positioned to reinforce said primary resilient means during forward over center movement thereof through said forward over center position and to release said reinforcement prior to return movement of said primary resilient means through said return over center position.
6. In an apparatus responsive to fluctuating actuating force, the combination comprising a plate spring having a bent portion and two ends extending therefrom, means for adjustably locating one end thereof, means for pivotally restraining said spring near the bent portion thereof, means for communicating said fluctuating actuating force to the opposite end of said spring for deflecting the same, a toggle link pivotally carried on a stationary pivot in position to be actuated by said spring upon deflection thereof and engaging said spring through resilient means stressed so as to hold the bent portion of said spring in engagement with said pivotally-restraining means, and auxiliary adjusting means for engaging said spring during a portion of the travel thereof.
7. In a pressure-responsive switch, the combination comprising a frame member having a base portion, a diaphragm chamber secured to the exterior surface of said base portion, a diaphragm clamped between said chamber and said base portion, a presser-foot engaging said diaphragm provided with a thruster extending through said base portion to the interior side

thereof, a plate spring disposed close to and in nearly parallel relation with the interior surface of said base portion in position to be deflected away from said base portion by said thruster, means adjustably engaging said spring for adjustably tensioning the same, over-center snap action means cooperatively engaging a deflectable portion of said spring, and a circuit interrupting means associated with said base in position to be actuated by said over-center snap action means.

8. In a pressure-responsive switch, the combination comprising a frame member having a base portion, a diaphragm chamber secured to the exterior surface of said base portion, a diaphragm clamped between said chamber and said base portion, a presser-foot engaging said diaphragm provided with a thruster extending through said base portion to the interior side thereof, a plate spring disposed close to and in nearly parallel relation with the interior surface of said base portion in position to be deflected away from said base portion by said thruster, means adjustably engaging said spring for adjustably tensioning the same, an aperture in said plate spring, toggle means including a toggle link and toggle tensioning means mounted within said aperture to be actuated by said plate spring, and circuit-interrupting means actuatable by said toggle means.

9. In a pressure switch, a sheet metal housing and mounting means therefor comprising a substantially flat rectangular base portion and two upwardly bent oppositely disposed parallel side portions, a diaphragm and diaphragm chamber disposed beneath said base portion and secured thereto with said diaphragm clamped between said base portion and said diaphragm chamber, a presser-foot disposed below said base and in engagement with said diaphragm, a thruster extending from said presser-foot through said base portion into the interior of said housing, a plate-spring disposed above said rectangular base portion in approximately parallel relation thereto, means associated with said base for causing said spring to oppose the action of said thruster, contactor mounting means disposed in bridging relation between and secured to said parallel side portions of said housing, fixed and movable contacts

mounted thereon, over-center snap action means associated with said spring adapted to be actuated thereby when said spring is deflected by said thruster, and means for causing said over-center means to act upon said movable contacts.

10. In a pressure-responsive switch, the combination comprising a frame member having a base portion having upstanding side portions open at the top, a diaphragm chamber secured to the bottom exterior surface of said base, a diaphragm clamped between said chamber and said base, a presser-foot engaging said diaphragm and provided with a thruster extending upwardly through said base, a plate-spring disposed upon and in nearly parallel relation with said base in position to be deflected upwardly by said thruster, means extending above said spring for adjustably tensioning the same, over-center snap action means cooperatively engaging a deflectable portion of said spring, a circuit-interrupting means supported above said base and spring in position to be actuated by said over-center snap action means, and terminals on said circuit-interrupting means accessible from a position above said spring and over-center snap action means.

11. In a pressure-responsive switch, the combination comprising a frame member having a base portion having upstanding side portions open at the top, a diaphragm chamber secured to the bottom exterior surface of said base, a diaphragm clamped between said chamber and said base, a presser-foot engaging said diaphragm and provided with a thruster extending upwardly through said base, a plate-spring disposed upon and in nearly parallel relation with said base in position to be deflected upwardly by said thruster, means extending above said spring for adjustably tensioning the same, an aperture in said plate-spring, toggle means including a toggle link and toggle-tensioning means mounted within said aperture to be actuated by said plate-spring, circuit-interrupting means mounted upon said base and spring and above said toggle means in position to be actuated thereby, and terminals on said circuit-interrupting means accessible from a position above said base, spring, and toggle means.

LYLE BEEMAN.
